SYSTEM AND MEANS FOR DIFFERENTIALLY METERING ELECTRICITY FOR LIGHTING AND HEATING PURPOSES.

1,298,649.

Specification of Letters Patent.

Patented Apr. 1, 1919.

Application filed July 8, 1916. Serial No. 108,146.

To all whom it may concern:

Be it known that we, LAWRENCE BIRKS, a subject of the King of Great Britain, and JOHN RICHARD TEMPLIN, a citizen of the 5 United States of America, residing at 10 Jackson's road, Fendalton, Christchurch, New Zealand, and 10 Wroxton Terrace, Fendalton, Christchurch, New Zealand, respectively, have invented new and useful 10 Improvements in Systems and Means for Differentially Metering Electricity for Lighting and Heating Purposes, of which the following is a specification.

This invention relates to the metering of 15 electricity as a basis of payment by the consumer and refers chiefly to cases where the supply is intended for domestic purposes.

It has been found in practice that, for 20 lighting purposes, electricity will successfully compete with other illuminants if re-tailed at a price which will be remunerative at all times to the supply authority, but for heating purposes it has been found necessary to supply current on a very much reduced rate, which will only prove remunerative if confined to non-lighting hours. It 25 becomes necessary therefore to so arrange the charges that the use of current for heating purposes will be discouraged during lighting 30 hours more especially during the maximum or "peak" load and for this purpose many different methods of charging have been proposed. The methods hitherto employed however have all been open to objection inasmuch as, in some cases, they have proved 35 ineffective for the purpose, while in other cases the complication of the system and the expense occasioned by the installation and maintenance of the necessary instruments, have rendered such systems unsatisfactory to both the consumer and the supply authority.

It is the object of the present invention therefore to overcome the difficulties hitherto experienced and to provide means whereby the customary forms of supply meters may be utilized to record directly all current supplied under the special differential rates.

In effecting this purpose the invention 45 consists essentially in the employment of two meters so controlled by a hand operated switch that, when the latter is in one

position, the heating circuits will be connected with the supply through the meter on which the low charge is made, while the 55 lighting circuits will be disconnected. Upon the switch being moved to its other position however the lighting circuits will be connected with the supply through the second meter on which the higher charge is made, 60 while the heating circuits will also be connected but through both meters, the result being that all current supplied for heating, while the switch is in the lighting position will be simultaneously recorded by both and 65 will therefore be charged for at the sum of the two rates.

The two meters as mentioned throughout the present specification and claims are not necessarily separate instruments but 70 may consist of what is termed a "double-rate meter", that is to say, a meter in which the parts are duplicated so as to embody in one instrument the equivalent of two meters and it must be clearly understood 75 that such is included in the scope of this invention.

In order that the nature of the invention and the manner in which it is to be performed may be clearly understood, reference will now be made to the accompanying sheet of diagrams, in which,—

Figure 1 illustrates the invention as applied to the ordinary watt-meters, and,

Fig. 2 shows the invention adapted for 85 use with coulomb-meters, or "ampere-hour-meters" as they are commonly termed.

Referring first to Fig. 1, A is the wattmeter through which current is supplied at the higher rate for lighting and B the wattmeter through which current is supplied at the lower rate for heating.

According to the present invention the series winding 1 of the meter A and the series winding 2 of the meter B are connected in 95 series by means of a wire 3, thus the current in passing from the main or phase wire 4 to the lead 5 of the heating circuit is caused to traverse the series windings of both meters.

The shunt winding 6 of the meter B is 100 permanently connected as by means of wires 7 and 8 connecting respectively with the phase wire 4 and the return or neutral wire 9 while the shunt-winding 10 of the meter

A is connected by means of the wire 11 and the wire 12 which passes through one pole of a double-pole switch 13.

The lead 14 of the lighting circuit is connected with the phase-wire 4 through the series winding 1 of the meter A and through the remaining pole of the double-pole switch 13.

When therefore the switch 13 is in the 10 position as here shown in full lines one pole of such will serve to connect the lead 14 of the lighting circuit through the series winding 1 of the meter A with the phase-wire 4, while the other pole will close the circuit 15 of the shunt winding 10 of such meter and when the switch is in the position indicated in dotted lines it will disconnect the wire 14 from the supply and open the circuit of the shunt 10.

20 The arrangement is such therefore that during the day-time when the current is not required for lighting, the switch will be placed in the dotted line position which permits of the heating circuit only being used 25 and for which the current passes through both the series windings 1 and 2 of the meters A and B. As however the shunt winding 10 is disconnected the meter A will be inoperative and consequently the current 30 so supplied will be recorded solely by the meter B on which the lower charge is made.

When current is required for lighting, however the switch is placed in the full line position which serves to supply the 35 lighting circuit through the series winding 1 of the meter A and also to close the circuit of the shunt 10 as above described, the result being that all current so supplied to the lighting circuit will be metered by the meter 40 A upon which the higher charge is made.

Should it be so desired however to utilize the heating circuit while the switch is in the lighting position, it will be understood that, as the heating circuit is supplied through 45 both meters and as both are in the operative condition, the current so supplied to the heating circuit will be recorded simultaneously by both meters and consequently the charge for such current will be at the sum 50 of the two rates.

Referring now to Fig. 2, which illustrates the application of the invention to forms of meters in which no shunt winding is provided, C is a coulomb-meter through which 55 current is supplied at the higher rate for lighting and D a similar instrument through which current is supplied at the lower rate for heating.

According to the present invention the 60 lead 15 of the heating circuit is connected through both meters C and D in series with the phase-wire 16. In this case a double throw-switch is employed and adapted when in the position here shown in full lines to 65 connect the lead 18 of the lighting circuit

through the wire 19 and meter C with the phase-wire 16, and when in the dotted line position to connect the wire 19 with the phase-wire 16 and so short-circuit the meter C.

By this arrangement therefore, when current is not required for lighting, the switch 70 17 is placed in the dotted line position thus disconnecting the lighting circuit and short-circuiting the meter C. The current so supplied to the heating circuit will therefore be metered solely by the meter D upon which the lower charge is made.

When current for lighting is required, the switch is placed in the full line position thus 80 connecting the lighting circuit with the phase-wire 16 through the meter C on which the higher charge is made. Should the heating circuit be used when the switch is in the lighting position however, it will be understood that as the short-circuit is removed, all current supplied to such heater circuit will 85 pass through and consequently be recorded by both meters C and D and will in consequence be charged for at the sum of the two 90 rates as in the case of the arrangement shown in Fig. 1.

Should it be so desired the same purpose may be effected in the case of Fig. 1, by con-

tinently in circuit and substituting for the double-pole switch a double-throw switch, adapted to alternately connect the lighting circuit with the phase-wire through the series winding of the meter A or to short-cir- 100 cuit such series winding for the purpose of supplying current to the heating circuit through the meter B alone in a manner similar to that shown in Fig. 2. This method is however considered to be inferior inasmuch 105 as the series winding, in consequence of its low resistance, would continue to carry a portion of the current in spite of the fact that it had been short-circuited and thus creepage of the meter A would occur.

We claim:

1. In combination, a source of current, a heating circuit, a lighting circuit, a pair of wattmeters having series and shunt windings, one for said lighting circuit and one for 115 said heating circuit, and a circuit controller capable of occupying one extreme position wherein current is supplied to the lighting circuit through the series windings of the lighting meter, and current is supplied to the heating circuit through the series windings of both of the meters, and another ex- 120 treme position wherein the lighting circuit is disconnected from the lighting meter, the shunt winding of the latter is on open cir- 125 cuit.

2. In combination, a source of current, a pair of watt-meters having series and shunt windings, a lighting circuit connected to the source of current through the series wind- 130

ings of one watt-meter, and a heating circuit connected through the series windings of both watt-meters, the shunt winding of one watt-meter being permanently connected to the source of current, and the shunt winding of the other meter being connected to the source of current only when the lighting circuit is connected to the source of current, and a circuit controller for connecting the lighting circuit to its respective meter

independently of the heating circuit and its meter.

In testimony whereof we have signed our names to this specification in the presence of two subscribing witnesses.

LAWRENCE BIRKS.

JOHN RICHARD TEMPLIN.
